TOY PROJECTILE

Leslie Armstrong, Detroit, Mich.

Application February 1, 1946, Serial No. 644,875

5 Claims. (Cl. 273—106)

1

This invention relates to improvements in toy projectiles, and more particularly to such a novel toy projectile in simulation of a rocket bomb.

A primary object of this invention is the provision of a self-propelling toy in simulation of a rocket bomb, such as the "V-2" type of rocket-propelled bomb or projectile.

An additional object of the invention is the provision of such a device wherein the propelling mechanism is entirely self-contained in the projectile, and may be reset and refired as many times as desired.

Still another object of the invention is the provision of such a device characterized by a relatively resilient nose, whereby damage to articles of furniture, in the event the device is fired indoors, is obviated.

Other objects will in part be obvious from and in part be pointed out in the following description of the invention and the accompanying drawings, wherein is disclosed a preferred embodiment of this inventive concept.

In the drawings:

Figure 1 is a side view, partially in elevation and partially in longitudinal section, disclosing one form of device embodying features of this inventive concept and showing the same in cocked position.

Figure 2 is a view similar to Figure 1, but showing the device in operated or projecting position.

Figure 3 is a rear end elevation of the device.

Similar reference characters refer to similar parts throughout the several views of the drawings.

Referring in detail to the drawings, the projectile of the instant invention comprises a body portion 10 of generally cylindrical shape terminating in a conical nose portion 11, the latter being preferably composed of rubber, or similar resilient material, precluding damage to any object struck by the projectile. The rear end of the body 10 is tapered, as at 12, and provided with an axial recess 13, having a reduced forward extremity 14. An annular flange 15 is provided in the rear end of the recess 13, defining a circular opening 16 smaller in diameter than the recess 13. Inserted axially in the recess 13 and slideable through the opening 16 is a cup-shaped tubular plunger 17 having a lateral flange 18 on its forward open end. A helical expanding spring 19 is inserted in the open end of the plunger 17 with its forward end abutting the forward end of the recess 13 and its rearward end abutting the closed rear end of the plunger, the ends of the spring being seated in the reduced recess portion 14 and closed rear end

2

of the plunger, respectively. In the expanded position of the spring 19 the plunger 17 is positioned rearwardly out of the recess 13 with its flange 18 urging the annular flange 15. Opposite sides of the forward part of the tapered rear portion 12 of the body 10 are formed with slots 20 opening into the recess 13, across which are fixed pivots 22 on which are pivoted lugs 21 projecting radially inwardly from forward portions of plate-like vanes 23 which are rearwardly elongated and extend longitudinally along the rear tapered body portion 12. The forward ends of the vanes have noses 23' which normally bear against the side of the body 10 forwardly of the slots 20. The lugs 21 are arranged to catch behind the plunger flange 18 to retain the plunger in forward cocked position.

As shown in Figure 3, fixed or stationary fins 24 may be fixed to the body 10 at right angles to the movable fins 23.

From the foregoing the operation of the device should now be readily understandable. The device is cocked by forcing the plunger 17 forwardly, while holding the body 10, so as to compress the spring 19 and permit the flange 18 to cam the lugs 21 aside and then be engaged behind the flange 18 on the forward end of the plunger 17, and thereby maintain the device securely in position for firing.

To fire the projectile, it is placed with its rear end against any suitable relatively unyielding back-stop surface and the movable vanes 23 then manually compressed toward each other, thereby releasing the lugs 21 from the plunger flange 18 and permitting the spring 19 to expand and forcibly drive the plunger 17 rearwardly until the plunger flange 18 strikes the annular flange 15. This action of the plunger 17 against the back-stop surface projects the projectile forwardly toward the target at which it was aimed.

Obviously, the range and trajectory of the device are determined by the angle at which the same is held against the back-stop surface.

From the foregoing it will now be seen that there is herein provided a device which accomplishes all the objects of this invention, and others, including many advantages of great practical utility and commercial importance.

Since many embodiments of the invention may be made, and since many modifications may be made in the embodiment hereinbefore shown and described, it is to be understood that disclosure made herein is to be interpreted merely as illustrative except as limited by the scope of the subjoined claims.

I claim:

1. A self-propelled toy projectile comprising an elongated body formed with an axial recess opening through its rear end, a tubular plunger axially inserted in and axially movable in said recess, a helical expanding spring having its forward end abutted with the forward end of said recess and its rearward end inserted in said tubular plunger, means at the rear end of said plunger against which the rear end of said spring abuts, said spring when in expanded condition being sufficiently long to position said tubular plunger partly out of the rear end of said recess and beyond the rear end of said body, and means on said body arranged to engage a portion of said plunger when pushed forwardly into said recess so as to compress said spring for holding said plunger in such forward position and manually releasable from said portion of the plunger so as to permit said spring to expand and drive said plunger forwardly out of said recess against a back-stop whereby said body is projected forwardly from the back-stop.

2. A self-propelled toy projectile adapted to project itself forwardly from a back-stop, said projectile comprising an elongated body formed with an axial recess opening through its rear end and extending forwardly for a substantial portion of the length of said body, a tubular plunger inserted endwise in said recess, the rear end of said plunger being closed and the forward end of said plunger being open and provided with a lateral stop flange and the rear end of said recess being formed with an internal stop flange against which said plunger flange can engage to stop further rearward movement of said plunger out of said recess, a helical expanding spring inserted in said tubular plunger with its rear end abutting the closed rear end of the plunger and its forward end abutting the forward end of said recess, said spring being arranged to expand sufficiently to position said plunger a substantial distance rearwardly beyond the rear end of said body, and releasable catch means on said body for engaging behind said plunger stop flange when said plunger is pushed to a forward position in said recess in which said spring is compressed, so as to retain said plunger in cocked position, said catch means being manually releasable to free said plunger and permit said spring to expand and drive said plunger rearwardly from said body against the back-stop and thereby project said body forwardly from the back-stop.

3. A self-propelled toy projectile adapted to project itself forwardly from a back-stop, said projectile comprising an elongated body formed with an axial recess opening through its rear end and extending forwardly for a substantial portion of the length of said body, a tubular plunger inserted endwise in said recess, the rear end of said plunger being closed and the forward end of said plunger being open and provided with a lateral stop flange and the rear end of said recess being formed with an internal stop flange against which said plunger flange can engage to stop further rearward movement of said plunger out of said recess, a helical expanding spring inserted in said tubular plunger with its rear end abutting the closed rear end of the plunger and its forward end abutting the forward end of said recess, said spring being arranged to expand sufficiently to position said plunger a substantial distance rearwardly beyond the rear end of said body, and releasable catch means on said body for engaging behind said

plunger stop flange when said plunger is pushed to a forward position in said recess in which said spring is compressed, so as to retain said plunger in cocked position, said catch means being manually releasable to free said plunger and permit said spring to expand and drive said plunger rearwardly from said body against the back-stop and thereby project said body forwardly from the back-stop, external circumferentially spaced vanes along a rear portion of said body for guiding the said body in projected flight.

4. A self-propelled toy projectile adapted to project itself forwardly from a back-stop, said projectile comprising an elongated body formed with an axial recess opening through its rear end and extending forwardly for a substantial portion of the length of said body, a tubular plunger inserted endwise in said recess, the rear end of said plunger being closed and the forward end of said plunger being open and provided with a lateral stop flange and the rear end of said recess being formed with an internal stop flange against which said plunger flange can engage to stop further rearward movement of said plunger out of said recess, a helical expanding spring inserted in said tubular plunger with its rear end abutting the closed rear end of the plunger and its forward end abutting the forward end of said recess, said spring being arranged to expand sufficiently to position said plunger a substantial distance rearwardly beyond the rear end of said body, and releasable catch means on said body for engaging behind said plunger stop flange when said plunger is pushed to a forward position in said recess in which said spring is compressed, so as to retain said plunger in cocked position, said catch means being manually releasable to free said plunger and permit said spring to expand and drive said plunger rearwardly from said body against the back-stop and thereby project said body forwardly from the back-stop, external circumferentially spaced vanes along a rear portion of said body for guiding said body in projected flight, some of said vanes being movably mounted on said body and having legs extending through slots formed in said body and opening into said recess, said legs constituting said releasable catch means and being retainably engageable in one position with said plunger stop flange and out of contact with said plunger stop flange in another position.

5. A self-propelled toy projectile adapted to project itself forwardly from a back-stop, said projectile comprising an elongated body formed with an axial recess opening through its rear end and extending forwardly for a substantial portion of the length of said body, a tubular plunger inserted endwise in said recess, the rear end of said plunger being closed and the forward end of said plunger being open and provided with a lateral stop flange and the rear end of said recess being formed with an internal stop flange against which said plunger flange can engage to stop further rearward movement of said plunger out of said recess, a helical expanding spring inserted in said tubular plunger with its rear end abutting the closed rear end of the plunger and its forward end abutting the forward end of said recess, said spring being arranged to expand sufficiently to position said plunger a substantial distance rearwardly beyond the rear end of said body, and releasable catch means on said body for engaging behind said plunger stop flange when said plunger is pushed to a forward position in said recess in which said spring is com-

pressed, so as to retain said plunger in cocked position, said catch means being manually releasable to free said plunger and permit said spring to expand and drive said plunger rearwardly from said body against the backstop and thereby project said body forwardly from the back-stop, said releasable catch means comprising circumferentially spaced flight guiding vanes on the rear part of said body having lugs projecting radially into said recess through slots formed in said body, means pivoting said vanes for movement toward and away from the side of the body, said lugs being arranged to be moved toward the side of the body for retainably engaging said lugs with said plunger stop flange in the outward position of the vanes and movable away from the

side of the body to release the lugs from said plunger stop flange.
